CLAIM

The ornamental design for a disc jockey turntable, as shown.

DESCRIPTION

FIG. 1 is a front perspective view of a disc jockey turntable showing our new design with cover removed for illustrative purposes;

FIG. 2 is a top view thereof;

FIG. 3 is a bottom view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top view of the disc jockey turntable showing our new design with cover installed for illustrative purposes;

FIG. 9 is a bottom view of our invention shown in FIG. 8;

FIG. 10 is a front elevational view of our invention shown in FIG. 8;

FIG. 11 is a rear elevational view of our invention shown in FIG. 8;

FIG. 12 is a left side elevational view of our invention shown in FIG. 8; and,

FIG. 13 is a right side elevational view of our invention shown in FIG. 8.
